LIQUID REFRIGERANT CONTROL MEANS FOR REFRIGERATING SYSTEMS

Application filed October 6, 1930. Serial No. 486,574.

Our present invention relates to means controlling the liquid refrigerant in refrigerating systems when desiring to sterilize the evaporator.

5 In certain kinds of liquid refrigeration, the liquids are cooled by allowing the same to flow over the evaporator of the system, particularly in systems where the evaporator is arranged in the form of an expansion coil. For 10 sanitary reasons, it becomes necessary to sterilize the evaporator frequently. This is usually accomplished by directing a spray of steam from a boiler against the evaporator. In order that the steam may quickly heat 15 the evaporator to the required temperature for sterilizing the coil, it is absolutely necessary that the liquid refrigerant be first removed from the evaporator. If this is not done, sufficient heat must be supplied to the 20 evaporator that the pressure therein (in ammonia systems) rises to a pressure of over nine hundred pounds per square inch in order to raise the temperature of the evaporator coils to a sterilizing temperature of about two 25 hundred twelve degrees. In practice, the liquid refrigerant is first pumped from the evaporator by closing the expansion valve and operating the compressor until the liquid 30 has boiled out of the evaporator, after which the evaporator may be easily heated by steam.

Our present invention and improvements in refrigerating systems dispenses with the necessity of pumping the liquid refrigerant from the evaporator or the creation of such 35 pressures.

An important object of our invention is to provide means for removing or receiving the liquid refrigerant from the evaporator soon after the compressor has been stopped and 40 keeping it out of the evaporator during the sterilization process and until the compressor is started again, and for normally retaining the liquid refrigerant in the evaporator as long as the compressor is in operation.

45 Another important object of our invention is to provide such means which, in certain forms, is entirely automatic in its action and requires no attention whatsoever.

A further object is to provide a novel and 50 simple means for storing the liquid refriger-

erant, normally contained in the evaporator, during sterilization of the evaporator.

A still further object of our invention is to provide simple means for maintaining the temperature of the liquid refrigerant storage 55 chamber at the desired temperature whereby the liquid refrigerant is normally forced into the evaporator, and to provide such temperature maintaining means which cooperate with the evaporator of the system and forms a 60 pre-cooling means therefor.

Another object of this invention is to provide liquid refrigerant control means of the class mentioned which is simple and economical of construction, installation, and 65 operation, and which will not readily deteriorate or get out of order.

With these and other objects in view as will appear hereinafter, we have provided a 70 refrigeration system having certain novel features of construction, combination and arrangement of parts and portions, as will be hereinafter described in detail and particularly set forth in the appended claims, reference being had to the accompanying drawing 75 and to the characters of reference thereon which form a part of this application in which:

The figure of the drawing is a fragmentary and diagrammatic elevational view of a 80 refrigerating system embodying our invention.

The refrigerating system illustrated in the drawing is one form of cooling apparatus for cooling such product as milk, and which, it 85 is necessary, to sterilize frequently. In this apparatus the milk is discharged into a distributor 1 from a tank 2 or other source of supply. From the distributor 1, the milk is directed downwardly, by gravity if desired, 90 over a pre-cooling coil and then over a final cooling coil. The pre-cooling coil 3 is positioned immediately below the distributor and immediately above the final cooling coil 4. From the coil 4, the cooled milk drops into 95 the tray or trough 5.

The final cooling coil 4 is the evaporator of the refrigerating system. The upper portion of the evaporator is connected by a conductor 6 to the upper portion of an accumula- 100

tor 7 which is also connected at its bottom end by a conductor 8 to the lower portion of the evaporator. The upper end of the accumulator 7 is connected by a conductor 9 to the suction end of the compressor 10. The discharge end or high pressure side of the compressor is connected to a receiver 11 in which the compressed refrigerant is liquefied. The receiver is also connected by a conductor 12 to the lower portion of the evaporator and of the accumulator through the conductor 8. In the conductor 12 is interposed an expansion valve 13 which, in this instance, is a hand controlled valve.

15 To the lower portion of the evaporator and the accumulator, and preferably to the conductor 8, which is connected with such portions of the evaporator and the accumulator, is connected the lower portion of a drum 20 or receptacle 14, by means of a conductor 15. Between the conductor 15 and the receptacle 14 is interposed a trap 16. The conductor 15 and the trap 16 are so positioned with respect to the lower portion of the evaporator that 25 all liquid refrigerant in the latter and in the accumulator is adapted to flow by gravity into the conductor 15 and the trap 16 and from the latter into the receptacle 14 which will be herein known as the liquid refrigerant 30 storage chamber. The liquid refrigerant is received and stored in the receptacle 14 when the pressure in the evaporator 4 exceeds the pressure in the receptacle 14.

35 The receptacle 14 or liquid refrigerant storage chamber is enclosed by a casing 17 which forms a water jacket therefor. This water jacket is continually supplied with water through a conductor 18 which extends from a pump 19 to the upper end of the water jacket. The upper end of the water jacket is also connected by a conductor 20 to the lower portion of the pre-cooling coil 3. Thus it will be seen that the pipes or conductors are so connected to the jacket that the cooling 45 liquid in the jacket will not be siphoned therefrom. The upper portion of the coil 3 may be connected by a conductor 21 to a cooler, not shown. The water from such a cooler may be the source of water for the pump 19. The 50 water passed through the water jacket 17 is at a temperature less than room temperature so that when the compressor 10 is stopped and the evaporator 4 heated to room temperature, the pressure in the evaporator will be 55 greater than that in the liquid refrigerant storage chamber 14 and force the liquid refrigerant into the storage chamber.

60 The operating principle of our invention in the refrigerating system is the direct relation which exists between the vapor pressure of a refrigerating fluid and its temperature. When the compressor is in operation and a quantity of liquid is in the evaporator, there is a flow of vapor through the suction line 65 9 to the compressor and a flow of liquid re-

frigerant from the receiver 11 through the expansion valve 13 to the evaporator, replenishing the liquid refrigerant therein which boils off during the process of refrigerating. During normal operation of the system, there is no liquid refrigerant in the receptacle 14, the vapor pressure therein being the same as that in the accumulator. The temperature of the liquid refrigerant in the evaporator must, for normal operation, be less than that of the cooling water in the water jacket 17. If, during normal operation, any liquid refrigerant passes the receptacle 14, it will vaporize and attempt to produce a vapor pressure in this receptacle which corresponds to the temperature of the water in the water jacket, forcing any liquid refrigerant from the receptacle 14 through the trap 16 into the conductor 15 and into the evaporator and accumulator.

80 When the compressor is stopped, the valve 13 is closed manually. Since the evaporator and the suction line 9 are exposed to room temperature, the liquid in the evaporator will boil until the pressure in the accumulator and suction line will correspond to such higher temperature. Due to the water trapped in the jacket 17, the liquid refrigerant storage chamber 14 will still be at the same temperature as when the machine 90 was in operation, and since the cooling water is assumed to have a temperature lower than that of ordinary room temperature, the vapor pressure in the chamber is now less than that in the evaporator, accumulator, or suction line, the liquid refrigerant in the evaporator is forced into the storage chamber, which is of a size sufficient to hold substantially all of the liquid refrigerant in the evaporator and accumulator. The liquid refrigerant will remain in the chamber 14 as long as the vapor pressure therein is less than in the evaporator, accumulator, or suction line. The evaporator or coil 4 may then be 100 sterilized with steam without creating excessive pressures in the system.

105 When the compressor is again started, the pressure in the evaporator, accumulator and suction line is reduced, and, when this pressure falls below that normally maintained in the storage chamber, the liquid refrigerant is forced from the storage chamber back into the evaporator, and the system is again ready for normal operation, and after 110 the valve 13 is reopened.

115 Our liquid refrigerant control means herein disclosed may be used with a refrigerating system employing an automatic float-type expansion valve, provided a shut-off is opened and closed in the liquid line from the receiver when the compressor is 120 started and shut down. The hand controlled expansion valve may be set for normal operation and left unchanged, provided there is only sufficient liquid refrigerant in the 125 130

entire system merely to fill the evaporator. The automatic diaphragm type of expansion valve may also be used, provided its closing pressure corresponds to a temperature which is somewhat lower than that of the cooling water in the water jacket.

Though we have shown and described a particular construction, combination and arrangement of parts and portions of our 10 liquid refrigerant control means and a particular application thereof to a refrigerating system of a particular type, we do not wish to be limited to this particular construction, combination and arrangement, nor 15 to the particular application, but desire to include in the scope of our invention the construction, combination and arrangement substantially as set forth in the appended claims.

Having thus described our invention, what 20 we claim as new and desire to secure by Letters Patent is.

1. In a refrigeration system, an evaporator adapted to contain liquid refrigerant, means for receiving the evaporated refrigerant from the upper portion of the evaporator and for compressing and supplying the same to the lower portion of the evaporator, a liquid refrigerant storage chamber communicating with the lower portion of the 25 evaporator and adapted to receive the liquid refrigerant therefrom when the pressure in the evaporator becomes excessive, a water jacket surrounding said chamber, means for supplying cooling water to the jacket, and 30 a pre-cooling means in association with the evaporator and connected to and adapted to receive the water from the jacket.

2. In a refrigeration system, an evaporator adapted to contain liquid refrigerant, means 35 for receiving evaporated refrigerant from the upper portion of the evaporator and for compressing the same, a receiver for receiving the liquefied refrigerant from the last mentioned means and connected to the lower 40 portion of the evaporator, a valve interposed in the connection between the receiver and the evaporator, a liquid refrigerant storage chamber communicating with the lower portion of the evaporator and adapted to receive 45 the liquid refrigerant therefrom when the pressure in the evaporator becomes excessive, a water jacket surrounding said chamber, means for supplying cooling water to the jacket, and a pre-cooling means in association 50 with the evaporator and connected to and adapted to receive the water from the jacket.

3. In a refrigerating system, an evaporator adapted to contain liquid refrigerant, an 55 accumulator connected at its upper portion with the upper portion of the evaporator and at its lower portion with the lower portion of the evaporator, means for receiving evaporated refrigerant from the accumulator and for compressing the same, the latter 60 means being connected with the lower portion

of the evaporator, a liquid refrigerant storage chamber communicating with the lower portions of the accumulator and evaporator and adapted to receive substantially all of the liquid refrigerant from both of the 70 latter, a water jacket surrounding said chamber, means for supplying cooling water to the jacket, and a pre-cooling means in association with the evaporator.

4. In a refrigerating system, an evaporator, a pre-cooling coil arranged above the evaporator and adapted for pre-cooling liquid directed over the evaporator, a liquid refrigerant storage chamber communicating with the evaporator and adapted to receive substantially all of the liquid refrigerant contained therein, a liquid cooling jacket surrounding the chamber, a liquid supply for the jacket, and means connecting the jacket to the pre-cooling coil.

5. In a refrigerating system, an evaporator, a pre-cooling coil arranged above the evaporator and adapted for pre-cooling liquid directed over the evaporator, a liquid refrigerant storage chamber communicating with the evaporator and adapted to receive substantially all of the liquid refrigerant contained therein, a liquid cooling jacket surrounding the chamber, a cooling liquid supply conductor connected to the upper portion of the jacket, and another conductor connecting the upper portion of the jacket to the lower portion of the pre-cooling coil.

6. In a refrigerating system, a pre-cooling coil, an evaporator coil positioned below the former, means for supplying liquid to be cooled to the upper portion of the pre-cooling coil, a compressor connected with the upper portion of the evaporator coil and connected at its pressure side to the lower portion of the evaporator coil, a valve between the pressure side of the compressor and the evaporator coil, a liquid refrigerant storage chamber adapted to receive the liquid refrigerant from the evaporator coil when the compressor is shut off, a cooling jacket surrounding the storage chamber, means for supplying a cooling liquid to the jacket, a conductor connecting the jacket to the lower portion of the pre-cooling coil, and a discharge for the pre-cooling coil.

7. In a refrigeration system, a pre-cooler, an evaporator adapted to contain liquid refrigerant, means for receiving the evaporated refrigerant from the upper portion of the evaporator and for compressing and supplying the same to the lower portion of the evaporator, a liquid refrigerant storage chamber communicating with the lower portion of the evaporator and adapted to receive the liquid refrigerant therefrom when the pressure in the evaporator becomes excessive, a water jacket surrounding said chamber means connecting said water jacket with said pre-

cooler, and means for supplying cooling water to the jacket.

8. In a refrigeration system, a pre-cooler, an evaporator adapted to contain liquid refrigerant, means for receiving evaporated refrigerant from the upper portion of the evaporator and for compressing the same, a receiver for receiving the liquefied refrigerant from the last mentioned means and connected to the lower portion of the evaporator, a valve interposed in the connection between the receiver and the evaporator, a liquid refrigerant storage chamber communicating with the lower portion of the evaporator and adapted to receive the liquid refrigerant therefrom when the pressure in the evaporator becomes excessive, a water jacket surrounding said chamber means connecting said water jacket with said pre-cooler, and means for supplying cooling water to the jacket.

9. In a refrigerating system, a pre-cooler, an evaporator adapted to contain liquid refrigerant, an accumulator connected at its upper portion with the upper portion of the evaporator and at its lower portion with the lower portion of the evaporator, means for receiving evaporated refrigerant from the accumulator and for compressing the same, the latter means being connected with the lower portion of the evaporator, a liquid refrigerant storage chamber communicating with the lower portions of the accumulator and evaporator and adapted to receive substantially all of the liquid refrigerant from both of the latter, a water jacket surrounding said chamber means connecting said water jacket with said pre-cooler, and means for supplying cooling water to the jacket.

40 10. In a refrigerating system, a pre-cooler, an evaporator, a liquid refrigerant storage chamber communicating with the evaporator and adapted to receive substantially all of the liquid refrigerant contained therein, a liquid cooling jacket surrounding the chamber and means connecting said water jacket with said pre-cooler.

11. In a refrigerating system, an evaporator, a cooling coil, a liquid refrigerant storage chamber communicating with the evaporator and adapted to receive substantially all of the liquid refrigerant contained therein, a liquid cooling container means associated with said chamber, a liquid supply for the container means, and means connecting the container means with the cooling coil.

12. In a refrigerating system, an evaporator, a pre-cooling coil, a liquid refrigerant storage chamber communicating with the evaporator and adapted to receive substantially all of the liquid refrigerant contained therein, a liquid cooling jacket surrounding the chamber, a liquid supply for the jacket, and means connecting the jacket to the pre-cooling coil.

13. In a refrigerating system, an evaporator, a pre-cooling coil, a liquid refrigerant storage chamber communicating with the evaporator and adapted to receive substantially all of the liquid refrigerant contained therein, a liquid cooling jacket surrounding the chamber, a cooling liquid supply conductor connected to the upper portion of the jacket, and another conductor connecting the upper portion of the jacket to the lower portion of the pre-cooling coil.

In testimony whereof, we have hereunto set our hands, respectively, at Los Angeles, California, this 29th day of September, 1930, and at Escondido, California, this 25th day of September, 1930.
